UNITED STATES PATENT OFFICE.

HENRY W. NAGEL, OF VICKSBURG, MISSISSIPPI.

SQUARE.

No. 797,453.

Specification of Letters Patent.

Patented Aug. 15, 1905.

Application filed June 10, 1904. Serial No. 212,005.

To all whom it may concern:

Be it known that I, HENRY W. NAGEL, a citizen of the United States, residing at Vicksburg, in the county of Warren, State of Mississippi, have invented certain new and useful Improvements in Squares; and I do hereby declare the following to be a full, clear, and exact description of the invention, such as will enable others skilled in the art to which it appertains to make and use the same.

This invention relates to bevels; and it has for its object to provide a construction which may be adjusted for use as an ordinary square or as a bevel, a further object of the invention being to provide a construction which will be cheap, simple, and durable and may be quickly and accurately adjusted.

In the drawings forming a portion of this specification, and in which like numerals of reference indicate similar parts in the several views, Figure 1 is a top plan view of a square embodying the present invention. Fig. 2 is a section on line 2-2 of Fig. 1. Fig. 3 is a section on line 3-3 of Fig. 1.

Referring now to the drawings, the present tool comprises a central plate 5, which forms what may be termed the "stem" of the square and which is provided with a longitudinal slot 6, extending throughout a portion of its length and for a purpose to be presently explained. The plate 5 is tapered at one end and to this tapered end portion against opposite faces thereof are pivoted arms 7 and 8, which are T-shaped in cross-section, as illustrated, the stems of the arms being disposed against the plate 5, while the head flanges are at right angles to the upper and lower faces of the plate. The head flanges of the arms terminate short of the pivoted ends of the arms, so that said arms may be folded close against the side edges of the plate 5.

Upon the plate 5 is slidably mounted a sleeve 9, having spaced ears 10 at each side thereof and between which at each side of the plate is pivoted a link 11 and 12, respectively, said links being pivoted at their outer ends against the stems of the arms 7 and 8, respectively, so that as the sleeve 9 is reciprocated upon the plate 5 the arms 7 and 8 are swung toward and away from said plate, so that they will lie

at various angles to each other. The upper and lower sides of the sleeve 9 are of sufficient resiliency to permit them to be drawn toward each other against the plate 5 to hold the sleeve against movement on the plate. To thus clamp the sleeve to the plate 5, a thumb-screw 15 is engaged loosely through the upper side of the sleeve and is screwed into the lower side of the sleeve, so that by adjusting the screw in one direction the sides of the sleeve will be brought together and by adjusting it in the opposite direction the sides of the sleeve will be released.

It will be noted that with the construction presented there is produced a tool which has great rigidity and durability.

The plate 5 is marked on the upper face near the slot 6 with a scale from which the sleeve 9 travels, the sleeve with the scale indicating the angle at which the arms 7 and 8 lie. It will be noted that the scale comprises four long markings, 20, 21, 22, and 23, which indicate, respectively, where to set the sleeve in order that the arms may lie at an angle corresponding to two sides of a square, a pentagon, a hexagon, and an octagon, respectively. The member 5 always bisects the angle between the arms. The long marks referred to are at one side of the slot. Between the long marks referred to are shorter marks 25, which in connection with the long marks form a pitch-scale and show the pitch of the bevel—that is, they indicate the rise in inches to the foot. It will of course be understood that one scale may be on one side of the plate and the other scale on the other side.

It will be of course understood that when the thumb-screw 15 is operated the sleeve will not only be compressed upon the plate 5 but also upon the links 11 and 12, so that all parts will be held securely against movement with respect to each other.

What is claimed is—

A square consisting of a plate 5 having a longitudinal slot therein and scales at opposite sides of the slot, a compressible sleeve 9 slidably mounted upon the slotted plate, said sleeve including spaced ears, links 11 and 12 pivoted between the ears at opposite sides of the plate, cross-sectional T-shaped arms 7 and

8 pivoted to one end of the slotted plate and pivoted to the links respectively, and a thumb-screw passed loosely through one side of the sleeve and through the slotted plate and screwed into the opposite plate and adapted to compress the sleeve against the slotted plate and the links.

In testimony whereof I affix my signature in presence of two witnesses.

HENRY W. NAGEL.
